UNITED STATES PATENT OFFICE.

JOB BORTON, OF BARNESVILLE, OHIO, ASSIGNOR TO WILLIAM H. HOBBS
AND JOHN S. SMITH, BOTH OF SAME PLACE.

IRONING-TABLE.

SPECIFICATION forming part of Letters Patent No. 319,445, dated June 9, 1885.

Application filed May 8, 1884. (No model.)

To all whom it may concern:

Be it known that I, JOB BORTON, a citizen of the United States, residing at Barnesville, in the county of Belmont and State of Ohio, have 5 invented certain new and useful Improvements in Ironing-Tables; and I do declare the following to be a full, clear, and exact description of the invention, such as will enable others skilled in the art to which it appertains to make and 10 use the same, reference being had to the accompanying drawings, and to the letters and figures of reference marked thereon, which form a part of this specification.

My invention relates to improvements in 15 ironing-tables; and it consists in the novel construction, combination, and arrangement of the several parts, as will be hereinafter more fully described and claimed.

In the drawings, Figure 1 is a side view of the 20 table ready for use. Fig. 2 is a vertical longitudinal section of same on line $x-x$, Fig. 4.

Fig. 3 shows the table when folded. Figs. 4 and 6 show end views of the table ready for use. Fig. 5 is a detail view of the iron-holder.

25 The board A may be of ordinary form, and is provided at what for convenience of reference I call its "rear end," with a metallic strap, a, extended across its upper face. In the middle of this rear end I form a slot, B, 30 the back wall b of which is beveled outwardly from its lower to its upper end, as most clearly shown in Fig. 2. The strap a above this slot B is slightly elevated, as shown in Fig. 4, to permit the point of the latch presently 35 described to be inserted thereunder, as will be understood from Figs. 2 and 4.

It is manifest that instead of elevating the strap a, as shown, a small groove might be cut in the face of the board to receive the point of 40 the latch, though I prefer to employ the strap, as shown.

The leg C is provided on its inner face with 45 blocks D, secured or formed thereon and set slightly apart to permit the end of the brace bar or leg E to be pivoted between them, as will be understood from Fig. 2. The upper ends of the blocks are flush with the end of the leg, so when the leg is turned down the blocks and leg will rest firmly against the under side of the board A. The blocks are

hinged at d to the under side of the ironing-board.

The brace or supplemental leg E has one end pivoted at e to and between the blocks D, and is extended beyond said pivot at e', so as to 55 bind against the inner side of leg C, when the parts are in position for operation, as shown in Figs. 1 and 2. When thus turned out, the ends of the brace-leg and leg C rest in the same plane, so as to support the board A in a level 60 position.

A rod, F, is hinged at one end to the brace-leg E, and has its opposite end bent or formed to engage a staple, f, secured on the inner side of and near the lower end of the leg C, and 65 serves to brace the supplemental leg from spreading away from the leg C. When the parts are folded together the rod F may be held to the leg E by catching it over a hook, E', secured to the under side of said leg, as 70 shown, as will be understood.

A latch-bar, G, is pivoted on the back of the leg C, and is provided with or has bent from its upper end a hook, g, constructed to fit over the rear end of the ironing-board and 75 under the strap a, the upper end of bar G resting in the groove B, as shown in Figs. 2 and 4. The latch-bar is extended at G' below its pivot, and a spring, H, bears between the leg C and the said extension G'. This spring operates to give the upper end of the latch a force or tension toward the leg C. When the leg C is folded under the board A, and it is moved out to bring the parts to the position shown in Figs. 1 or 2, the hook g will be engaged by 85 the beveled wall b of the slot B, and will be guided thereby into position under the strap a. The side walls of the slot B prevent the lateral displacement of latch G, as will be seen most clearly from Figs. 1 and 2.

The iron-holder I is provided with a shank, i. This shank is pivoted on and near the rear end of the board A at about the central point between its extremity and the holder I.

A catch, J, is pivoted at one end on the rear 95 of the ironing-board, and is provided in its upper edge with a groove, j, fitted to receive and hold the shank of the iron-holder. The movable end of this catch is actuated by a spring, K, which holds it normally up in po- 100

sition to engage the shank, so as to keep the holder from being swung on its pivot by any slight jolt or jar. It will be seen that the holder will be caught by the catch J when 5 turned over on or out from the end of the board A.

The operation of my invention is simple and readily understood. It is an object in tables of the class to which this invention relates to 10 construct them so they may be conveniently folded into a small space and as conveniently set up for use. In my table it will be seen from Fig. 3 the parts may all fold into compact form, the blocks D enabling the board A 15 and legs C E to rest close together. When desired for use, the table may be easily set up, this operation requiring merely the unfolding of the parts and the catching of the rod F into 20 staples f, the latch G moving automatically into its desired position. It is manifest that 25 instead of the specific preferred form of latch shown and before described, an ordinary hook could be secured on the leg C, and operate in connection with a staple on the rear end of the ironing-board to secure the parts together.

Having thus described my invention, what I claim, and desire to secure by Letters Patent, is—

1. In an ironing-table, the combination of 30 the ironing-board, the leg C, pivotally secured to and near the rear end of the said board, a latch, G, pivoted to the rear side of said leg C, and having its upper end fitted to engage the rear end of the ironing-board, and pro-

vided with an extension, G', below its pivot, 35 a spring bearing between the leg C and extension G, and a support for the other or front end of the board, substantially as set forth.

2. The combination, in an ironing-table, of the board A, a strap, a, extended across the 40 rear end of same, blocks D D, hinged at their forward upper sides to the underside of board A and set slightly apart, the leg C, secured to the rear side of and movable with the blocks D, the latch G, pivoted to the leg C, fitted at 45 its upper end to engage the board A, and provided with an extension, G', a spring, H, bearing between the leg C and extension G', the leg E, pivoted to and between the blocks D, and a stay-rod, F, all arranged and operating substantially as and for the purposes specified.

3. The combination of the board A, provided in its rear end with a slot, B, having beveled wall b, the straps a, secured on the rear end 55 of board A, and elevated or bulged above slot B, the leg C, pivotally secured to the board A, and the latch G, pivoted to the leg C, and provided at its upper end with a hook fitted to engage under the strap a, and to be guided 60 into such engagement by beveled wall b of slot B, all substantially as set forth.

In testimony whereof I affix my signature in presence of two witnesses.

JOB BORTON.
